(57) **CLAIM**

The ornamental design for a rear bumper for a vehicle as shown and described.

DESCRIPTION

This application contains subject matter related to the following co-pending U.S. design patent applications:

Application Ser. No. 29/858,131, filed Oct. 28, 2022 and entitled “Rear Bumper for a Vehicle”; and
Application Ser. No. 29/898,196, filed herewith and entitled “Rear Bumper for a Vehicle”.

FIG. 1 is a front view of a rear bumper for a vehicle according to the design;

FIG. 2 is a left, bottom perspective view thereof;

FIG. 3 is a right, front perspective view thereof;

FIG. 4 is a left side view thereof;

FIG. 5 is a right side view thereof;

FIG. 6 is a top view thereof;

FIG. 7 is a bottom view thereof; and,

FIG. 8 is a rear view thereof.

The broken lines in the drawings depict portions of a rear bumper for a vehicle that form no part of the claimed design.

1 Claim, 8 Drawing Sheets
